Attorney

UNITED STATES PATENT OFFICE.

HENRY PUFF, OF LOS ANGELES, CALIFORNIA.

CAMPER'S FOLDING TABLE.

1,368,452.

Specification of Letters Patent. Patented Feb. 15, 1921.

Application filed May 29, 1920. Serial No. 385,286.

To all whom it may concern:

Be it known that I, HENRY PUFF, a citizen of the United States, residing at Los Angeles, in the county of Los Angeles and State of California, have invented certain new and useful Improvements in Campers' Folding Tables, of which the following is a specification, reference being had to the accompanying drawings.

10 This invention relates to foldable tables, and particularly to tables adapted to be folded in compact form and carried on automobiles or in other vehicles for use in camping out or under like circumstances.

15 The general object of my invention is to provide a table so constructed that the legs may be folded up within the leaves of the table and the table leaves folded against each other so as to form a carrying case, as it may be termed.

20 A further object is to provide a construction of this character in which the legs are very strongly and firmly connected to the leaves forming the top of the table and in 25 which the legs are firmly braced in their vertical, operative position when turned at right angles to the table top.

25 A further object is to provide simple means for locking the two sections or leaves 30 of the table in alined position when the table is in use and bracing the middle of the table against sagging, and in this connection to provide an improved form of hinge for engaging the sections of the table top with 35 each other which will prevent sagging of the table top at the joint between the two sections.

40 Still another object is to provide a foldable shelf normally carried within the foldable table top, but when in use adapted to be supported by the legs and held from accidental detachment from the legs.

45 Other objects will appear in the course of the following description.

50 My invention is illustrated in the accompanying drawings, wherein:—

Figure 1 is a perspective view of a table constructed in accordance with my invention;

55 Fig. 2 is a perspective view of the table folded up;

Fig. 3 is a perspective view of the lower shelf of the table folded up;

Fig. 4 is a fragmentary top plan view of one end of the table; 55

Fig. 5 is a fragmentary side elevation of one end of the table;

Fig. 6 is a bottom plan view of the table in its open condition;

Fig. 7 is an enlarged fragmentary top 60 plan view to show the manner of connecting the braces to the cleats;

Fig. 8 is a fragmentary top plan view of one corner showing the brace engaging the cleat when the leg is open; 65

Fig. 9 is a section on the line 9—9 of Fig. 8;

Fig. 10 is a section on the line 10—10 of Fig. 7.

Referring to the drawings, it will be seen 70 that the table top comprises two sections 10 and 11. These leaves or sections have attached to the margins of the under face the end cleats 12 and the side cleats 13 and 14. Thus each leaf is thoroughly braced by the 75 end cleats 12 and the side cleats 13 and 14 so that each leaf is strong. The leaves 10 and 11 are connected to each other by hinges, designated generally 15 and which will be later described, these hinges being 80 located at the ends of the leaves and connecting the leaves to each other so that the leaves may be folded in one direction into parallel relation to each other but will be held in the same plane when the outer faces 85 of the cleats 13 confront each other.

Attached to each end cleat 12 of each section 10 or 11 is a bracket 16 having outwardly projecting ears 17 at its opposite ends. This bracket is made of strap iron 90 and is held to the corresponding cleat by screws or other means. Coacting with each bracket 16 is a leg 18, and passing longitudinally through the ears 17 and through a perforation in the butt end of the leg is a 95 rod 19 screw-threaded at its outer end for the reception of a nut 20 holding the leg in place on the rod and against the adjacent ear 17. The opposite end of the rod 19 from the nut 20 is angularly bent, as at 21, 100 to pass the adjacent ear 17 and then extends inward and toward the free end of the leg 18, and when it reaches the leg is bent, as at 22, parallel to the leg to brace it and then is passed transversely through the leg and is 105 screw-threaded at its extremity for engage-

ment by a nut 23. Thus the leg is thoroughly braced and mounted at the same time for rotative movement on the ears 17.

- For the purpose of holding these legs in position at right angles to the plane of the table top formed by the leaves 10 and 11, I attach to each leg a spring brace, designated generally 24. One end of this brace is angularly bent and passed through a perforation 10 in the leg, as at 25, and carries a nut 26. The opposite end of the spring brace 24 is angularly bent, as at 27, and extends into a slot 28 formed in the inner face of the corresponding cleat 13, this slot extending longitudinally 15 of the cleat but at a slight inclination thereto, as shown clearly in Fig. 7, and the slot at that end which is nearest to the inner face of the cleat 12 is angularly directed, as at 31. The brace 24 is, as before stated, of 20 resilient metal and when the leg is folded against the face of the leaf it is disposed in the slot 28 in the manner illustrated in Fig. 7, but as the leg is turned into angular relation to the plane of the table leaf, the angular 25 terminal 27^a of the bent end 27 travels along the groove 28^a of slot 28 and the free end of the spring brace is gradually forced outward as the leg turns to its depending position until the angular end 27 of the brace reaches 30 the portion 31, when the resilience causes the angular end 27 to spring into the portion 31, thus locking the leg in its vertical position, that is in a position at right angles to the table top (see Fig. 8). When it is desired 35 to release the brace, the free end of the brace is simply pulled outward from the notch or recess 31 until the terminal portion 27^a is again in line with the groove 28^a, and then the leg may be folded against the leaf until 40 the leg lies flat against the table top. What is true of one of the legs is, of course, true of all of the legs.

- For the purpose of supporting a shelf below the table top when the legs are unfolded, I pivotally mount upon two of the legs the cross pieces 32 which, when the legs are folded, lie flat against the upper faces of the legs, but which, when the legs are unfolded, may be turned to extend laterally. The free ends of these cross pieces 32 or supports are slotted or notched, as at 33, to engage with studs 34 on the opposite pair of legs. These braces, therefore, brace the legs laterally. The sectional shelf, as illustrated 50 in Fig. 3, consists of two sections 35 and 36 hinged to each other at 37 and the under faces of these sections 35 and 36 being provided at their ends with transverse pairs of cleats 38 and a groove 39 adapted to engage 55 over the braces 32. When the leaves 35 and 36 are folded into parallel relation, they are disposed within one of the sections of the table and thus inclosed within the folded table top.

- 60 While I do not wish to be limited to any

particular form of hinges for connecting the two sections of the table top to each other, I have illustrated a hinge 15 on the order of a rule joint, this hinge consisting of two leaves *a* and *b*, the leaf *a* having an off-set 70 circular lug *c* and the leaf *e* having a lug *d* which is not off-set but which fits against the off-set lug, these lugs being connected to each other by a transverse pintle *f*. Inasmuch as the lugs *c* and *d* extend downward, 75 it is obvious that when the hinge leaves are brought into alignment that the ends of the hinge leaves will abut against each other, thus holding the sections of the table top from being forced downward at their joint 80 and preventing the table top from sagging and holding it very rigidly and firmly. In order to still further prevent any tendency of the table top to sag at the joint and to still further hold the two sections of the 85 table top in alignment with each other, I preferably form the conjoined cleats or strips 14 with transverse alining slots 40, and dispose within one of these slots a short supporting bar 41 of metal which is pivoted, 90 as at 42, to one of the cleats 14 and which is provided with a handle or finger piece 43. Thus when the table is in use, this supporting bar 41 is turned at right angles to the length of the cleats 14 so as to extend on 95 opposite sides of the cleats and beneath the joint of the leaves, and on the other hand, when the leaves are folded, this member 41 is turned into alignment with the cleat 14 to which it is pivoted and thus permits the sections to be folded, the finger piece 43 lying close against the inner face of the cleat.

A table constructed in accordance with my invention is very simple and is very compact, can be easily carried upon the running board 100 of an automobile, or placed in convenient position in any vehicle. It is very light and is particularly strong. It will be noted that the legs are very strongly braced by the angular bend 22 in the braces formed by the 105 bar 19, and that thus the legs are held from any lateral bending strain. This is particularly necessary in camping tables, which are liable to be subjected to rough usage. The resilient braces 24 will prevent the legs from 110 folding down accidentally. The shelf is firmly supported in place and is particularly convenient for holding dishes in convenient position for service while the table is being used for eating.

120 Preferably the sections 10 and 11 will be provided at either side edge with hooks whereby they may be latched together in the position shown in Fig. 2, and with coacting handle straps.

I claim:—

1. A table having a table top, brackets attached to the under side of the table top and having outwardly projecting ears at their opposite ends, a leg for each bracket 1

and disposed against one of said ears, a brace for each leg bent to extend through both of said ears and one end of the leg, the outer end of the brace being bent angularly inward toward the leg, then extended along the leg and against the same and then laterally bent to extend through the leg and be attached thereto, and braces pivoted to the corresponding legs and operatively 10 engaging the corresponding leaf and shiftable therewith and locking the leg when the leg is turned to a position at right angles to the plane of the leaf.

2. In a table, a table top having along one margin thereof and on its under side a longitudinally extending cleat, said cleat at its junction with the table top being formed to provide a longitudinally extending slot, the slot extending at an angle to the longitudinal axis of the cleat and toward the hinged end of the leg and at its end adjacent the hinged end of the leg having an outwardly extending, offset portion, the wall of the slot being formed with an upwardly extending groove opening into said off-set portion, and a resilient brace pivoted to the leg and at its end being angularly bent to extend into said slot and again angularly bent to extend into said groove, the resilience of the brace urging its free end outward whereby, when the leg is turned into a position at right angles to the table top, the resilience of the brace will force its free angular end into said off-set portion of the groove and slot.

3. A foldable table having four legs operatively hinged to the table top and movable into or out of parallel relation thereto, a pair of supporting members pivoted to the legs on one side of the table for movement into a position parallel to said legs to which they are pivoted or into a position at right angles thereto, the free ends of said supporting members being notched and the opposite pair of legs being provided with studs over which said notches engage, and a shelf engageable with said supporting members, said shelf being formed in two hinged sections foldable upon each other, the inner faces of said hinged sections being provided with spaced cleats to engage over said supporting members.

4. A foldable table comprising two table top sections hinged to each other, each of said sections having cleats attached to its under face along the margins of the sections, means for locking said sections in alined relation or permitting the sections to fold over upon each other, a pair of legs hinged to the ends of each section and foldable into position against the inner face of each section or into position at right angles thereto, a brace for each leg engageable with

the corresponding cleat permitting the leg to be shifted into its supporting position or laid flat against the inner face of the corresponding section, the cleats and braces being formed to automatically lock the braces in engagement with the cleats when the legs are turned into a position at right angles to the leaves to which they are pivoted.

5. A foldable table comprising a table top formed in two sections hinged to each other for movement into a position of alinement or into parallel relation, each of said sections on its inner face having marginal cleats, brackets attached to the end cleats of each section of the table on the inside faces of the cleats, each bracket having two spaced ears, a rod passing through said ears, a leg carried by said rod and bearing against one of said ears, the opposite end of the rod being bent to form a brace and engaged at its end with the leg, the cleats being formed with longitudinally extending slots having outwardly extending notches or off-sets at their ends, and resilient braces for each leg pivotally attached thereto and at its free end being angularly bent to engage in said slot, the resilience of the braces urging their free ends outward whereby, when the legs are brought into position at right angles to the table top, the angular ends of the braces will spring into said off-set portions of the slot, two supporting members pivoted to two of the legs and having notches at their free ends, the other two legs being provided with studs with which the notches are adapted to engage, and a foldable shelf formed in two sections hinged to each other, the sections on the inside faces being provided with transversely extending, spaced cleats adapted to engage over said supporting members, the sections when folded being adapted to be disposed in the space defined by the cleats of one of said sections of the table top.

6. A table including a table top, legs hinged to the under side of the table top for movement into or out of parallel relation thereto, braces holding the legs at right angles to the table top, supporting members pivotally connected to two of said legs and foldable into or out of parallel relation thereto, the ends of said supporting members being notched, studs projecting from the other two legs with which the notched ends of the supporting members engage, and a foldable shelf formed in two sections hinged to each other and adapted to engage with said supporting members, said sections of the shelf, when folded, fitting into the table top sections when the latter are closed.

In testimony whereof I hereunto affix my signature.

HENRY PUFF.
